PORTABLE MOTION PICTURE PROJECTOR

William H. Bauch, Shelbyville, Ind., assignor to
 Pembroke W. Cornelius, Indianapolis, Ind.,
 doing business under the name and style of
 Cornelius Engineering Company

Application August 23, 1933, Serial No. 686,420

10 Claims. (Cl. 88—17)

This invention relates to the art of motion picture and sound on film projecting and reproducing machines and has for one of its primary objects the insulating of the film moving mechanism as related to the optical system from the sound reproducing system whereby the reproduced sound will be free from the otherwise interference set up by vibrations and noise arising particularly from the intermittent mechanism.

A further important object of the invention is to provide a structure that may be embodied in separate units capable of being attached and detached one from the other so that a portable machine may be produced to have a very low weight and still utilize the standard width films. It is my intention to provide a structure of the nature above indicated which may be perfectly reliable under all operating conditions and be so constructed that the various units may be easily and quickly assembled wherever the machine is to be employed. Many other objects and advantages of the invention will become apparent to those versed in the art in the following description of the invention as illustrated by the accompanying drawings, in which

Fig. 1 is a front elevation of a machine embodying my invention;

Fig. 2, a left hand side elevation;

Fig. 3, a rear elevation;

Fig. 4, a left hand elevation on an enlarged scale showing the units in a disassembled relation;

Fig. 5, a right hand elevation;

Fig. 6, a detail in right hand vertical elevation on a further enlarged scale;

Fig. 7, a detail in vertical section on a still further enlarged scale;

Fig. 8, a detail in side elevation of the "sound" assembly, and

Fig. 9, a top plan view of the "sound" assembly.

Like characters of reference indicate like parts throughout the several views in the drawings.

I provide a suitable base 10 here shown as having front and rear mounting brackets 11 and 12 respectively to adjustably support the base. On this base 10, I secure a motor attaching bracket 13 to which the operating motor 14 is secured. Preferably a control switch and outlet box 15 is also attached to the bracket 13. A horizontally disposed shelf 16 is provided on the top side of the bracket 13 toward the forward side thereof and a vertically disposed plate 17 extends upwardly from the bracket 13 to have

a centrally disposed, reinforcing web 18 provided between the rear side of the plate 17 and the top of the bracket 13. The plate 17, Fig. 3, is provided with a pair of slots 19 and 20 extending vertically downward from the top edge of the plate.

The principal actuating mechanism is carried within a housing 21 which has a base 22 adapted to rest on the shelf 16 with a rear face 23 extending vertically upward therefrom adapted to fit against the front side of the plate 17. A pair of cap screws 24 and 25 are screw-threadedly engaged in the housing 21 to extend from the face 23 rearwardly and slidably enter within the slots 19 and 20 so that the heads of the screws may be brought up to bear against the rear side of the plate 17 and thereby firmly secure the housing 21 to the bracket 13.

On the back side of the housing 21 toward the left side thereof, I attach a bracket 26 to have a rearwardly extending arm with a smooth vertically disposed face on the right side thereof, against which a plate 27 may be carried in sliding contact. This plate 27 has a rib 28 extending laterally under the extending arm of the bracket 26 to be normally in contact therewith. A thumb screw 29 is carried through a slot 30 in the arm of the bracket 26 to screw-threadedly engage the plate 27 so that the plate 27 may be shifted horizontally along the bracket 26 arm within the limits of the length of the slot 30. The plate 27 is attached to the lamp housing 31. The slot 30 is of such length and is so located in reference to the housing 21 that when the screw 29 is carried to the extreme rear end of the slot, the housing 31 will then be correctly positioned to properly focus the light coming from the housing and traversing the machine housing 21.

When the screw 29 is carried to the extreme forward end of the slot 30, the lamp housing 31 is then moved to its forward limit of travel whereby the forward end of the lamp housing is then adjacent the rear side of the housing 21 with only that amount of clearance therebetween which will prevent damage to the adjacent parts. The shiftable mounting of the lamp housing thus described is provided to permit the carrying of the lamp housing 31 in close relation with the machine housing 21 while the projector is being transported or is in storage and is further provided so that the housing 31 when in the rearwardly extended position is properly positioned.

A cord 32 extends from the under side of the lamp housing 31 and is provided with an attach-

ing plug 33 to be entered into the top side of the switch box 15. Also on the rear side of the machine housing 21 and below the bracket 26 is mounted an exciter lamp housing 34 from which a cable 35 leads to be interconnected through the switch box 15 by the plug 36. A light sensitive cell housing 37 is mounted on the forward face of the housing 21. A cable 38 leads from this cell to any suitable amplifying means (not shown). The forward and under faces of the housing 21 are joined by an oblique face 39. Against this face 39 is positioned the foot 40 of a film reel box 41, the box being there retained by means of studs 42 and 43 extending through slotted ears 44 and 45 of the film box to be engaged by thumb nuts 46 and 47.

The upper side of the housing 21 is horizontally disposed and receives thereon the film box 48 removably secured by means of the studs 49 and 50 extending through the box ears 51 and 52 to receive the thumb nuts 53 and 54.

Referring now principally to Fig. 6, a film 55 is carried downwardly from the upper box 48 to be threaded around the reel withdrawing sprocket 56 and thence upwardly and around in a free loop to be carried downwardly through the optical film gate 57, thence around the framing spool 58 and up over the intermittent drive sprocket 59, from which the film 55 is allowed to hang in a free loop. From this last loop, the film is carried over the constant drive sprocket 60, from which the film is then directed downwardly through the "sound" gate 61 from which the film is then carried into the box 41, which box has a central shaft 62 carrying a pulley 63 which is belt driven from the main drive shaft 64. Particular attention is invited to the fact that all of the film shifting sprockets above indicated are revolvably supported on a sub-frame 65. There is but one other driving sprocket than those above mentioned and this is the sprocket 66 which is below the sound gate 61 employed to pull the film through the gate 61. This sprocket 66, it is to be noted, is mounted directly upon the shaft 64.

The sub-frame 65 consists in reality of a pair of spaced apart plates 67 and 68 which supports the intermediate gearing between the sprockets 56, 59 and 60, such intermediate gearing not being shown since it is well known to those versed in the art and its details do not enter specifically into my invention. It is sufficient to state that in this transmission system, the usual Geneva star intermittent drive is employed in connection with a sprocket 59, this intermittent mechanism being confined within the box 69, Fig. 6. This intermittent type of drive which, as is well known, is employed to intermittently draw the film 55 past the light aperture in the gate 57 whereby the film as in the usual practice is permitted to come to a complete stop for each frame. The employment of this intermittent drive sets up quite a little vibration as well as noise and I have found in practice that where this mechanism is employed in the same machine which is utilized to reproduce sound from a light track on the film, such sound and/or vibration seem to effect the reproduction of this sound. I find that if the sub-frame 65 which supports the various driving sprockets, the transmission gearing therebetween, and the intermittent drive itself, is insulated from the housing 21, then there is no interference from this driving mechanism what-

soever and a more perfect reproduction of the sound is obtained.

To this end, the entire sub-frame 65 is insulated from the housing 21 by a structure now to be described. The back plate 68 of the sub-frame 65 is supported from the left side of the housing 21 by means of a plurality of screws 70, here shown as three in number, two at the top and one at the bottom, Figs. 2, 4, 6 and 7. Since direct connection of the screw with the housing 21 and the sub-frame would transmit vibrations and sound, I provide insulating means comprising an insulating thimble 71 through which the screw 70 passes and provide a socket on the inner side of the housing wall into which this thimble fits snugly. I further interpose a cork washer 72 between the outer end of the thimble 71 and the base of the socket. Concentrically with the inner socket is an outer socket in which is placed a cork washer 73 to bear against the base of the socket and then a metallic washer 74 against which the head of the screw 70 bears. The screw 70 in each case screw-threadedly engages the plate 68 so that by drawing up the screw 70, the various insulating members, the thimble 71, and washers 72 and 73 are compressively drawn toward the intervening annular flange 75 which separates and defines the two sockets above indicated.

In further reference to the power drive of the projecting machine, the motor 14 is provided with a driving pulley 76 here shown as being of the double sheave type to carry the pair of belts 77 and 78 which pass around the larger driven pulley 79 which is fixed to the shaft 64. This shaft 64 is revolvably carried by the housing 21 through the lower portion thereof to carry the lower sprocket 66 as above indicated. This shaft 64 further carries a pulley 80 within the housing 21. A window is provided in the housing so that a belt 81 may be carried about the pulley 80 and also about the pulley 63 frictionally carried on the shaft 62 mounted in the lower film box 41 as a means of rewinding the film. The shaft 64 is not gear connected with the film movement mechanism insofar as the optical system is concerned but is drivingly connected therewith by means of a chain 84.

The sub-frame 65 with its driving members carried thereby constitutes a separate assembly which may be assembled outside of the machine and then positioned therein without having to try to get at the various parts within the limited space provided and trying to assemble them as has heretofore been the practice. The assembly is sufficiently narrow in width to permit clearance for the centrally positioned lens tube 85 which telescopes by its rear end with the gate mechanism more particularly described in another application about to be filed by me. The spool 58 employed in framing is carried by a slide 86 which is in turn shifted by means of the hand lever 87, the particular operating mechanism for adjusting this framing roller being well known to those versed in the art.

Below the assembly 65 above described, I mount another sub-assembly which embodies the means for transposing light beam fluctuations set up in passing a beam of light through the film "sound track" into electrical fluctuations. This "sound" sub-assembly comprises essentially a base plate 90, a slit plate 91, the film gate 61, a lens system carried within the tube 92, and the photo-electric cell housing 37, Figs. 6, 8 and 9. The assembly is made up as a unit and then

placed in the frame 21 and secured thereto by screws 94.

The film gate 61 comprises a tubular member 95 which is supported from the base 90 by a bracket 96, here shown as being an integral part of the tube, a shiftable tubular telescoping tube 97, a head 98 on the tube 97, a cam lever 99, and the slit plate 91. The cam lever is revolvably carried on the tube 97 to bear against the tube 95 under the pull of the spring 109 which is fixed between the bracket 96 and the head 98, the film 55 passes between the plate 91 and the head 98. The cell housing 37 is fixed to the bracket 96. A lateral spacing roller 101 is also carried by the base plate 90 to align the film 55 in relation to the slit plate. It is highly important that the lens tube and the slit plate 91 be exactly aligned, and further that the parts be so related that should they vibrate, they do so in unison so that 10 the light beam as emanating from the exciter lamp 102 does not vibrate or shift in relation to the plate 91 which shifting would materially affect the sound reproduction. Hence the lens tube and slit plate are assembled by means of a 15 suitable aligning fixture and tools, the tube 92 being supported in the aligned position by the bracket 103 which extends from the base plate 90.

It is thus to be seen that from the foregoing description I have been able to produce a very 20 compact device capable of being assembled in two principal units with the additional units embodying the upper and lower film cases or boxes, and thereby have provided a structure which may be easily transported in a "knocked down" condition and then assembled where used. Further 25 by making a complete sub-assembly of the film moving mechanism insofar as the optical system is concerned, I am able to effectively insulate the noises and vibrations arising from such mechanism from a sound reproducing system carried 30 by the same supporting housing.

While I have herein shown and described my invention in the one best form as now known to me, it is obvious that structural variations may 45 be employed without departing from the spirit of the invention and I therefore do not desire to be limited to that precise form beyond the limitations as may be imposed by the following claims.

I claim:

1. In a portable motion picture projector, a 50 base, a central housing above the base, a motor carried by the base, a principal actuating mechanism housing detachably carried in the central housing, upper and lower film boxes detachably 55 carried by the central housing, a projector lamp carried by the central housing, and means adjustably permitting shifting of the lamp housing toward the central housing for a carrying position, said means automatically limiting the outward shifting of the lamp housing to the correct 60 focusing position.

2. In a portable motion picture projector, a base, a motor carried by the base, an optical mechanism housing detachably carried by the 65 base, upper and lower film boxes detachably carried by the housing, a projector lamp carried by the housing, and means adjustably permitting shifting of the lamp housing toward the housing for a carrying position, said means limiting the outward shifting of the lamp housing to the correct 70 focusing position, said base having a frame fixed thereto with an upper shelf, a vertically disposed plate extension from the frame having open end slots therein, said mechanism housing 75 having a base fitting on said shelf to have said

plate extend upwardly along the housing, and screws carried by the mechanism housing entered in said slots.

3. In a motion picture projector for projecting pictures, a housing, a sub-frame mounted in the housing, a sub-assembly embodying a film feed mechanism for the picture projection mounted in the sub-frame and removable therewith as a unit, a plurality of screws extending through said housing without touching the housing and engaging 5 said sub-frame, a thimble around each screw spacing the sub-frame from the housing and seated in a centering socket in the housing, the heads of the screws being outside of the housing, and insulating members interposed between the 10 screwhead and the housing and between the thimble and the housing.

4. In a portable motion picture projector, a base, a motor carried by the base, an optical mechanism housing detachably carried by the 20 base, upper and lower film boxes detachably carried by the housing, a projector lamp carried by the housing, and means adjustably permitting shifting of the lamp housing toward the housing for a carrying position, said means limiting the 25 outward shifting of the lamp housing to the correct focusing position, said base having a frame fixed thereto with an upper shelf, a vertically disposed plate extension from the frame having open end slots therein, said mechanism housing 30 having a base fitting on said shelf to have said plate extend upwardly along the housing, and screws carried by the mechanism housing entered in said slots, an oblique face interconnecting said housing base and its front side, and said lower 35 film box being secured to said oblique face.

5. In a motion picture projector, a central housing having a plurality of holes and insulating sockets concentric with the holes, a sub-frame supported by and within the housing, mechanism 40 for carrying a film located within the sub-frame and removable as a unit therewith, insulations seated in the sockets in the housing screws much smaller in diameter than the diameter of the holes passing through the sockets and insulation 45 and seated in the sub-frame and means cooperating with the sockets to space the sub-frame from the housing and to center the screws in the holes so they will not touch the housing.

6. In a motion picture projector, a central housing having a plurality of insulation sockets and an annular flange in each socket dividing it into inner and outer compartments, a sub-frame supported by and within the central housing, film mechanism located within the sub-frame and removable therewith as a unit, thimbles seated in the inner compartments of the central housing sockets and bearing against the sub-frame, and a screw for each socket having its head in the outer compartment of the socket passing through 50 holes in the flanges, much larger than the screws, without touching the flanges and passing through the thimble in the inner compartment and seated in the sub-frame.

7. In a motion picture projector, a central housing having a plurality of insulation sockets and an annular flange in each socket dividing it into inner and outer compartments, a sub-frame supported by and within the central housing, film mechanism located within the sub-frame and removable therewith as a unit, thimbles seated in the inner compartments of the central housing sockets and bearing against the sub-frame, a screw for each socket passing through holes in 65 the flanges, much larger than the screws, without 70 touching the flanges and passing through the thimble in the inner compartment and seated in the sub-frame.

touching the flanges and passing through the thimble in the inner compartment and seated in the sub-frame, and cork washers contacting each side of the annular flange in each socket.

5. In a motion picture projector, a base, a motor, a motor attaching bracket secured to the base, said motor secured in the bracket, said bracket having a top vertically disposed plate with vertical slots, a housing above the bracket having a vertical face fitting against the plate, cap screws threadedly engaging the housing and slidably entering the slots of the plate, said housing having the principal actuating mechanism of the projector supported as a unit within the 10 housing and insulated therefrom.

9. In a motion picture projector, a base, a motor, a motor attaching bracket secured to the base, said motor secured in the bracket, said bracket having a top vertically disposed plate with 20 vertical slots, a housing above the bracket having a vertical face fitting against the plate, cap screws threadedly engaging the housing and slidably entering the slots of the plate, said housing having the principal actuating mechanism of the

projector supported as a unit within the housing and insulated therefrom, a lower film reel-box supported by the housing, an upper reel-box supported upon the housing, a lamp, and means for adjustably supporting the lamp from the housing. 5

10. In a motion picture projector, having a base, a motor, a motor-attaching bracket secured to the base, said motor being secured within the bracket, of a horizontally disposed shelf on top of the bracket having a vertically disposed plate, 10 said plate having vertical slots entering from the top edge of the plate, in combination with a housing resting upon the shelf and having a vertical face fitting against the plate, said housing containing the principal actuating mechanism of the 15 projector, and cap screws threadedly engaging the housing and slidably entering the slots of the plate, said housing having a lower film reel box supported by the housing, and having an upper reel box supported upon the housing, and also 20 having a lamp and means for adjustably supporting the lamp from the housing.

WILLIAM H. BAUCH.
